VACUUM TANK

Filed Feb. 16, 1929

UNITED STATES PATENT OFFICE

CHARLES S. BURTON, OF OAK PARK, ILLINOIS

VACUUM TANK

Application filed February 16, 1929. Serial No. 340,352.

The purpose of this invention is to provide an improved construction in a vacuum tank adapted to facilitate dispensing with a valve to control the suction connection without creating the embarrassment which is liable to accompany the omission of the suction valve. It consists in the elements and features of construction shown and described as indicated in the claims.

It is well understood by those familiar with vacuum fuel feeding devices, that when, for any reason, in a vacuum tank the valve usually provided for controlling the suction port is omitted, it is necessary to limit the size of the suction port to a very small fraction of the atmosphere port and valve, in order that the opening of the atmosphere valve shall reduce the vacuum to a degree to permit the chamber of convenient depth to discharge by gravity for a substantial portion of the depth. And it is also well understood that the relatively large size of the atmosphere valve necessitates a correspondingly large float to have the buoyant value necessary for breaking the suction hold on the valve for opening it when the chamber is filled and should be discharged.

Dispensing with the valve at the suction port thus creates the dilemma that if the suction port is made large enough to ensure rapid filling of the vacuum chamber with fuel, the atmosphere port must be so large that the float required to break the suction hold must be very large and the vacuum chamber correspondingly large without enlarged fuel capacity around the float, thus rendering the total construction large and correspondingly expensive and inconvenient for installation on engine or vehicle suction.

On the other hand, if the suction port is made small enough to permit the atmosphere port to be small enough to require a valve small enough to be broken from the suction hold by a moderate size float, the fuel feeding capacity is rendered undesirably low.

This dilemma is avoided in the present invention by the expedient of getting the atmosphere valve, which is stressed to its seat inwardly with respect to the vacuum chamber by the suction, with another element also arranged to be stressed inwardly by the same

suction, the connection between the two elements being arranged to oppose the two stressed to each other, so that they are substantially counter-balanced; and however large the atmosphere inlet port may be made, the counter-balancing element may be made of equal or nearly equal exposure to the suction, so that the valve will be held to its seat by only the amount of pressure which is produced by the relative dimensions of the parts for causing the valve to be thus held by the minimum force judged necessary to insure that it will not be jarred from its seat by the running of the engine or the travel of the vehicle.

The character of this expedient adapts it to be employed either in a construction in which the atmosphere valve is seated interiorly, so as to be held to its seat by the suction, as in the usual vacuum tank construction, or in a construction in which that valve is located exteriorly of the vacuum chamber and would be unseated by the suction; for the counter-balancing element may be arranged in either case for experiencing the suction in the same direction as the valve, and may be connected for transmitting the stress in the reverse direction for counter-balancing the stress on the valve.

In the form of the invention shown in the present application the atmosphere valve is a slide valve arranged for requiring very short sliding movement for opening an atmosphere inlet of relatively large area, the valve and a part of the chamber wall comprising the port being in the form of grating, the wall having a multiplicity of relative long and narrow parallel slots spaced apart somewhat more than their width, and the valve being identically formed for seating and sliding on a slotted area of the wall constituting thus the valve seat, the open position of the valve being with its slots registered with the slots of the seat, and the sliding movement from this position a distance very slightly more than the width of the slot, serving to put the valve in closed position.

The slide valve is shown mounted for seating interiorly of the chamber wall, and is held yieldingly against the seat, so that the suction

due to vacuum in the chamber tends to relax the pressure of the valve on its seat.

The valve is operated for sliding to open and close by a lever which is operated by a float in the chamber, the valve being moved for opening when the float is lifted to a predetermined height by the rise of the liquid to a predetermined high level in the chamber, and being moved for closing when the float is lowered by the subsidence of the liquid to a predetermined low level.

In the drawings:

Figure 1 is a vertical section of a vacuum tank embodying this invention.

Figure 2 is a top plan view of the same.

Figure 3 is a detail section at the line 3—3 on Figure 2.

Figure 4 is a duplication of the upper part of Figure 1 on an enlarged scale.

The vacuum chamber is seen at A; the outer or main body member constituting the customary reserve fuel chamber is indicated at B. C is a cap which closes both chambers at the top and secures them together by means of an annular stamping, H, formed zigzag in radial section, lapping and soldered outside the body member, B, and lapping inside a peripheral flange, 10, of the cap under a marginal flange, 11, of the chamber, A. The three parts, viz., the annular stamping, H, which is permanently attached to the chamber, A, the chamber, B, and the cap, C,—are separably secured together by bolts, 12, with suitable packing gaskets, 13, interposed for liquid-tight junction between the cap and the vacuum chamber, B, an atmosphere vent fitting, M, being mounted in the lapped flanges, 10 and 11, and the web of the cap, C.

The fuel inlet fitting is seen at D. The fuel outlet fitting is seen at E, and a suction connection fitting is seen at F.

The slide valve, controlling the atmosphere inlet, is seen at G, having a plurality of parallel slots, 20, arranged and dimensioned for registration with the atmosphere inlet slots, 30, which are formed in a plate, K, which is mounted exteriorly of the cap, C, covering a relatively long narrow slot, 40, in the cap, C, in which slot the valve, G, is fitted for sliding longitudinally, the valve being enough shorter than the slot to permit its movement in the slot from open to closed position, that is, from the position at which the slots, 20, of the valve register with the slots, 30, of the plate to a position at which the slots of the plate are closed by the valve lapping the plate slots.

For upholding the valve in position in the slot, 40, of the cap and seated against the under side of the plate, K, there is provided a spring bar pressure lever, L, fulcrumed at 21 on a bracket, 22, which depends from the cap, C, said lever having at one end a roller, 23, which bears upwardly against the under side of the slide valve, G, at a middle portion

of the length of that valve at which the valve is without transverse slots, the plate, K, having a corresponding portion of its length without slots. The other end of the spring bar lever, L, is connected to a stem, 41, of a diaphragm, N, which constitutes the movable wall section exposed exteriorly to atmospheric pressure and interiorly to the sub-atmospheric pressure due to the engine suction through the suction connection, F, the suction obtaining restricted access to the vacuum chamber by the small port, 50, in the restriction fitting, F¹, at which the fitting, F, is connected to the vacuum chamber.

The diaphragm stem, 41, is adjustable at its connection with a spring bar lever, L, by hemispherical nuts, 41^a, which by their hemispherical form render the connection somewhat pivotal, and by their adjustment serve for adjusting the pressure of the slide valve, G, against its seat on the plate, K, to render that pressure, independently of the action of the diaphragm, N, due to the vacuum in the chamber, only sufficient to insure perfect touch between the valve and the seat, and to insure that the valve shall not be jarred out of touch by the vibration of the engine or jolting of the vehicle.

For operating the valve there is provided a bell crank lever, P, fulcrumed at 35 on a bracket, 36, depending from the cap, C, to which is attached striding the slot, 40, as seen in Figure 3, the upstanding arm, 37, of said lever engaging a notch, 43, in the end of a downwardly projecting lug, 46, formed at the end of the slide valve, G.

The horizontally extending arm, 38, of the lever, P, carries a depending rod, 49, on which between upper and lower stops, 51 and 52, thereon a float, S, is guided in up and down movement as it is buoyed by the liquid contained in the chamber.

The horizontal arm of the lever, P, may be threaded as seen at 44 for carrying a weight, T, adjustable for adjusting the device in respect to frictional resistance offered by the slide valve and connections, to the stress exerted by the buoyant effort of the float for opening movement of the valve. And in respect to this feature of the device and its operation it may be noted that the limited frictional pressure of the valve against its seat on the plate, K, will cause the float, arrested in its rising movement as the liquid level rises when it encounters the stop, 51, to stand at the level at which it is thus stopped while the liquid level continues to rise until the increased submersion of the float develops its buoyancy to a degree sufficient to overcome the frictional resistance of the valve; and that when this stage is reached and the further upward movement of the float and connections begins, the inertia of the moving parts will insure the completion of the very short movement of the valve to

wide-open position. And it will be observed that the purpose of the adjustable weight, T, is to supplement the float and lever in respect to the inertia, and to supplement the friction 5 of the valve on its seat for delaying the float until its increased submersion and consequently increased buoyant value shall be adequate to insure that the valve shall derive a complete opening movement when the float 10 starts after being stopped by the stop, 51.

When the liquid level subsides by the gravity discharge from the chamber, B, lowering the float into contact with the lower stop, 52, the float will be halted by the frictional resistance of the valve until the further subsidence of the liquid level, reducing the submergence of the float, brings its weight 15 into operation to a sufficient extent to overcome said frictional resistance and start the valve back to closed position; and as in the opening movement, the distance from open to closed position being very short, the inertia 20 of the parts when they begin to move will insure the completion of the movement to fully 25 closed position of the valve.

I claim:—

1. A construction for lifting liquid by suction, comprising a vacuum chamber having a suction connection, a liquid inflow connection, 30 an atmosphere inlet port and a liquid discharge port, a valve controlling the atmosphere inlet port arranged for suction action theron holding it against its seat, a limited portion of the chamber wall being inwardly 35 and outwardly movable without opening the wall, operating connections between the valve and said movable wall part arranged for opposing the suction action on the latter to the suction action on the valve; a float in the 40 chamber and connections from the float to said operating connections adapted to move the valve in opening direction upon the float being lifted by the rise of the liquid in the chamber to a predetermined high level, and 45 to move the valve in closing direction upon the subsidence of the liquid to a predetermined low level.

2. In the construction defined in claim 1, the operating connections between the movable 50 wall member and the valve being dimensioned relatively to the port area of the valve and the movable area of the movable wall member for approximately equalizing the opposite actions of the suction on said 55 movable wall member and valve respectively.

3. In the construction defined in claim 1, the lever mechanism being dimensioned relatively to the movable area of the movable wall member and the port area of the valve for approximately balancing the opposite movement-inducing force of the suction in the chamber on said valve and movable wall member respectively, and means additional to the 60 balanced force exerted by the movable wall

member for yieldingly resisting the withdrawal of the valve from its seat.

4. In the construction defined in claim 1, the movable wall member being a flexible diaphragm, the lever mechanism being dimensioned relatively to the flexible area of the diaphragm and the port area of the valve for approximately balancing the opposite movement-inducing force of the suction in the chamber on said valve and diaphragm respectively, and the spring reacting on the diaphragm, stressing it inwardly with respect to the chamber for overbalancing the suction action on the valve in opposite direction. 70

5. In the construction defined in claim 1, the movable wall member being a flexible diaphragm, the lever mechanism consisting of a lever of the first class, the connection from the float being made to said lever at a point of the lever at the opposite side of its connection with the diaphragm from the lever fulcrum; whereby leverage is afforded in favor of the buoyant effort of the float for 80 overcoming the excess of the force exerted through the diaphragm for holding the valve seated, over the suction action on the valve for unseating it. 85

6. In the construction defined in claim 1, the valve being a slide valve, a lever separate 90 from the first mentioned operating connections constituting the means by which the float operates the valve, the float being associated with said separate lever for actuating it in opposite directions at the limits of the rising and descending movement of the float for opening and closing the valve in said rising and descending movements respectively. 95

7. In the construction defined in claim 1, means for applying pressure for holding the valve against its seat adapted to render said pressure slightly in excess of the pressure due to action of the vacuum on the movable wall member. 100

8. In the construction defined in claim 1, the valve being seated interiorly of the chamber, whereby the suction tends to relax its pressure on its seat, the operating connections being also within the chamber and being connected to the movable wall member by a stem of the latter, said stem being exteriorly accessible for adjustment for applying to the valve pressure thereon seatward. 110

9. In the construction defined in claim 1, the valve being seated interiorly of the chamber, the operating connections being a lever of the first class having its fulcrum and end connections inside the chamber, one of its connections being adjustable to press the valve against the seat independently of the counter-balancing action of the movable wall member due to suction thereon, said adjustable connection comprising an exteriorly ac- 120

125

130

cessible part arranged for manipulation to effect such adjustment.

10. In the construction defined in claim 1, the valve being a slide valve, a lever separate from said operating connections first mentioned, operatively connected with the valve for sliding it, the float being connected with said separate lever for actuating it at predetermined limits of the rising and descending movements of the float due to change of level of the liquid content of the chamber.

11. The construction defined in claim 1, the valve being a slide valve seated exteriorly of the chamber, means for causing the pressure of the valve on its seat to exceed the force exerted by the movable wall member due to suction; a bell crank lever fulcrumed within the chamber having an upstanding arm engaging the valve, and a horizontally extending arm for connection with the float, and a weight adjustable on said horizontal arm for adapting the pressure exerted by said weight to the frictional resistance of the valve movement due to said excess.

25 12. In the construction defined in claim 1, the valve being a slide valve, a lever separate from said operating connections connected with the valve for sliding it for opening and closing at the limits of the rising and descending movements respectively of the float, and means connecting the float with said separate lever arranged to be engaged by the float at said limits.

35 13. In the construction defined in claim 1, the valve being a slide valve, the operating connections being arranged for affording a slide bearing for the valve, and exteriorly accessible means for adjusting the stress of the lever mechanism on the valve.

40 14. In the construction defined in claim 1, the valve being a slide valve seated interiorly of the chamber, whereby suction tends to withdraw it from its seat, and the operating connections being arranged for operating against the valve and affording a slide bearing for the latter, and exteriorly accessible means for adjusting the stress of the lever mechanism on the valve.

45 In testimony whereof, I have hereunto set my hand at Chicago, Illinois, this 13th day of February, 1929.

CHARLES S. BURTON.
